UNITED STATES PATENT OFFICE.

JOHN A. MAYBERRY, OF BELL, CALIFORNIA, ASSIGNOR OF ONE-FIFTH TO THOMAS A. MAYBERRY, ONE-FIFTH TO JAMES T. MAYBERRY, ONE-FIFTH TO GEORGE O. HEFFNER, AND ONE-FIFTH TO W. E. ALDERSON, ALL OF HUNTINGTON PARK, CALIFORNIA.

CROWN MOLD.

Application filed June 21, 1923. Serial No. 646,787.

To all whom it may concern:

Be it known that I, JOHN A. MAYBERRY, a citizen of the United States, residing at Bell, in the county of Los Angeles and State of California, have invented new and useful Improvements in Crown Molds, of which the following is a specification.

My present invention is a crown mold, and it is an especial object of this invention to 10 provide simple and effective means for use in the production of suitably tapered and curved blocks for use in constructing the tops or crowns of cesspools, or the like.

It is an object of this invention to 15 provide a mold comprising a minimum number of parts and suitable means for connecting or disconnecting said parts; and, in a preferred embodiment of my invention, my mold may consist essentially of a back plate 20 which may have an inward curvature and may be provided with flaring ends, and a front or closure plate, correspondingly curved, and optionally provided with suitable positioning lugs or stops and with a 25 somewhat extensive basal flange, suitable for use in retaining this element, or an entire mold, in an upright or other desired position, the two elements of my mold being connected in any suitable way.

It is a further object of my invention to 30 provide a crown mold of a type which may be utilized, by mere changes in dimension, in the production of either comparatively large or comparatively small crown blocks, my mold being preferably of such construction as to require neither a bottom element 35 nor a top element; and, in a preferred construction, either the body element or the supplemental closure element may be 40 removed from a block, after the molding of the same, without disturbing the block or the other element of my mold, the respective elements of said mold being connected by simple means, such as a pair of latches 45 pivoted to said body element.

Other objects of my invention will appear from the following description of a preferred embodiment thereof, and from the appended claims, taken in connection with the accompanying drawings, in which:

Figure 1 is a perspective view of one form of complete mold, in readiness for filling.

Fig. 2 is a perspective view of a back

or body element comprised in said mold.

Fig. 3 is a similar perspective view of 55 a cooperating front or closure element, adapted to be associated with the body element shown in Figure 2, in the production of a complete mold of the character shown in Figure 1.

Fig. 4 is a perspective view of a crown block such as may be formed by the mold shown in Figures 1, 2 and 3.

Figs. 5 and 6 are perspective views of alternative forms of blocks which may be 65 produced by molds of the general character herein described.

Fig. 7 is a perspective view of a removable ring which may optionally be used in connection with mold elements of the character shown in Figures 2 and 3.

Referring in detail to that specific embodiment of my invention which I have chosen for purposes of illustration, as will be understood from an inspection of the 75 drawings, my crown block mold consists essentially of two cooperating elements, one of these being a body portion or element 1, which may be provided with a tapered and inwardly convexed surface 2, whose upper 80 edge 3 and lower edge 4 may be substantially parallel, and which may be laterally terminated by downwardly and outwardly flaring, integral sides 5, whose top edges 6, 6' may be respectively parallel with the 85 bottom edges 7, 7', and whose horizontal diameter may be uniform, the free edge of each of the said sides being extended to form guide wings 18, provided with guide slots 9, adapted to receive interfitting projections 90 10, upon a correspondingly tapered closure element 11.

The tapered closure or cover element 11 may be so constructed that its upper edge 12 and its lower edge 13 shall be substantially 95 parallel with one another and with the upper and lower edges of the body element already described; and this closure element may be provided not only with the mentioned guiding projections 10, adapted to 100 enter the respective guiding slots 9 in the wings 8, but also with positioning stops or lugs 14, adapted to overlie the edges of the respective sides 5, shown as integral with the body element of my mold, and also with 105 a basal flange 15, by which the said closure

element, or the entire mold, may be retained in a upright or inclined, or other desired position, locking means, such as a pair of latches 16, shown as pivoted to the body element of my mold, being optionally provided to retain the mentioned parts in their desired relationship during the filling of a mold and during the setting of a block formed therein.

It will be obvious that when a mold of the character described is supported upon a flat surface, the upper and lower edges of the mold being shown as parallel and substantially horizontal, neither a bottom nor a top element is required, the flange 15 being suitably secured, as may be done by merely standing thereon, when my crown block mold is placed upon a floor or the like, or as may be done by extending said flange under any suitable projection or projections, such as fingers 17, which may be suitably secured to a table top, or the like. Any suitable plastic mixture, such as a comparatively dry concrete mixture, may be delivered into my mold through the open top thereof, suitably tamped therein, when desired, and allowed to set sufficiently to permit of the withdrawal of one or both of the described mold elements and a re-use thereof in the formation of additional blocks, said blocks being afterward moistened or cured in a known manner, the porosity of the block depending upon the character of the mixture employed and the density imparted thereto by tamping, as may be required for the various uses to which the blocks are to be put, comparatively porous blocks being entirely suitable for use in the construction of cesspools, or the like.

Although it will be obvious that suitably tapered crown blocks of various curvatures may be formed by a mold of the general character described, limiting cases in which curvatures become straight lines being suggested in Figures 5 and 6, it should be understood that the relationships between the respective inner faces of a mold of the character herein described are intended to be such as to produce blocks so proportioned that an intergral number thereof may be assembled to constitute a complete circle, in the manner of a hollow frustum of a cone or pyramid, the lateral faces of the respective blocks being adapted to contact in planes respectively intersecting the vertical axis of a cesspool, or the like, in whose crown they may be employed; it being understood that, when more than one tier of blocks are to be employed in the crown of a cesspool, the molds employed in the construction of the blocks for an upper tier shall be of such reduced dimensions as to permit of the use of an identical number of blocks, such as six blocks, in each of the successive tiers, the lateral surfaces of all

blocks being preferably vertical, and the top and bottom surfaces of all blocks being preferably horizontal, and the joints between successive tiers of blocks being broken.

In the construction of an ordinary cesspool, two tiers of crown blocks, each tier comprising six blocks, may advantageously be employed, my preferred construction being such that the blocks of each tier are mutually supporting and adapted to co-operate in resistance to vertical or lateral pressure, and such that the central opening left at the top of the uppermost tier of blocks may be closed by a simple flat plate or ordinary manhole cover.

When a lateral opening is to be provided in a cesspool; or the like, a suitable removable ring 18, such as is shown in Figure 7, may be inserted at a desired level during the filling of a mold, the ends of this ring being preferably cut to conform with the respective curvatures of the mold elements 1 and 11.

Although the flange 15, upon one of my mold elements, may be comparatively short or narrow, I prefer to make this element comparatively broad and heavy, it being obvious that every increase in the size of this element tends to increase the stability of my mold. It is advantageous to make the flange so broad that the center of gravity of a complete mold, or that of a mold and its contents, shall fall within the base thereof; and it will be understood that the crown blocks formed by a mold of the character described may advantageously be formed and cured upon separate palettes, in a known manner.

Although I have herein described but one complete embodiment, it will be understood that various features thereof might be independently employed, and also that various modifications might be made therein without departure from the spirit and scope of my invention, as the same is indicated above and in the following claims:

What I claim is:

1. In a crown mold, a body element having an inward convexity and associated with downwardly and outwardly flaring sides each provided with a guide slot to receive locking means.
2. In a crown mold, a tapered closure plate having parallel top and bottom edges and provided with a basal flange.
3. In a crown mold, a tapered body element and a correspondingly tapered closure element cooperating therewith to form a complete mold without top or bottom, said mold being provided with a basal flange.
4. In a crown mold, a tapered body element, and a correspondingly tapered closure element cooperating therewith to form a complete mold without top or bottom, said mold being provided with means to retain

the same in an upright or inclined position.

5. In a crown mold, a tapered body element, and a correspondingly tapered closure element cooperating therewith to form a 5 complete mold without top or bottom, and a removable ring adapted to extend between and conform to said mold elements.

10. In a crown mold, a body element having an inward convexity and downwardly and outwardly flaring sides, each provided with a guide slot and a tapered closure plate having projections fitting in the guide slots, and means for holding the plate in position between the sides.

15. 7. In a crown mold, a body element having an inward convexity and associated with downwardly and outwardly flaring sides, each provided with a guide slot and a tapered closure plate fitting between the sides 20 and having projections fitting in the guide slots and having positioning stops to fit the edges of the sides, and latches pivoted against the sides to engage the projections.

8. In a crown mold, a body element having an inward convexity and downwardly 25 and outwardly flaring sides, each provided with a guide slot and a tapered closure plate having projections fitting in the guide slots, means for holding the plate in position between the sides, and a basal flange extending 30 from the large end of the closure plate.

9. In a crown mold, a body element having an inward convexity and associated with downwardly and outwardly flaring sides, each provided with a guide slot and a tapered closure plate fitting between the sides and having projections fitting in the guide slots and having positioning stops to fit the edges of the sides, latches pivoted against the sides to engage the projections, and a 35 40 basal flange extending from the large end of the closure plate.

In testimony whereof I have signed my name to this specification.

JOHN A. MAYBERRY.
